UNITED STATES PATENT OFFICE.

EDUARD LEISSNER, OF NEW YORK, N. Y.

DESIGN FOR WALL-PAPER.

SPECIFICATION forming part of Design No. 18,148, dated August 8, 1882.

Application filed June 30, 1882. Term of patent 3½ years.

To all whom it may concern:

Be it known that I, EDUARD LEISSNER, of New York, in the county and State of New York, have invented a new and Improved Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

The figure A is circular, with leafy projections on each side and dots between these projections. The figure D resembles a flower with a circular center and pointed surrounding leaves. The figure C has an oval center with leaves branching off from it. The figure a is a circular flower-like figure. The b has an oval center with alternate round and pointed leaves surrounding it. d has a circular center surrounded by tulip-shaped leaves. The figure e resembles a half-closed sunflower. f is a branch

bearing tulip-like leaves. In the interstices between these figures run series of bars parallel to each other, and broken by the figures, with dots occasionally interspersed.

I claim—

1. The design for wall-paper, consisting of the figure A, substantially as shown.
2. The design for wall-paper, consisting of the figure D, substantially as shown.
3. The design for wall-paper, consisting of the figure b, substantially as shown.
4. The design for wall-paper, consisting of the figure a, substantially as shown.
5. The design for wall-paper, consisting of the figure C, substantially as shown.
6. The design for wall-paper, consisting of the figure d, substantially as shown.
7. The design for wall-paper, consisting of the figures A, D, C, a, b, d, e, and f, substantially as shown.

EDUARD LEISSNER.
